CHATTER ELIMINATOR FOR ROAD MAIN-
TENANCE MACHINES

Le Grand H. Lull, Austin, Minn.

Application May 23, 1931, Serial No. 539,491

8 Claims. (Cl. 37—143)

In road maintenance machines, such as scrapers, which are sometimes called patrols and which have a scraper blade adapted to scrape the surface of the road over which they travel, the vibration in the machine sets up a chattering which is submitted to the scraper blade and the result is a washboard-like road. This is a very undesirable result and I have designed a chatter eliminator adapted to overcome these objections.

10 This chatter eliminator for road maintenance machines is adjustably mounted on the scraper blade and operates as a bracket to steady the blade in its scraping operation over the surface of the road.

15 A feature resides in an adjustable brace which is adapted to contact with the surface of the road and which steadies the scraper blade in its travel over the road surface so that chattering of the scraper blade is eliminated, as well as permitting an increased speed of operation in miles per hour in road maintenance machines so that a decrease in the cost of maintenance is accomplished with my chatter eliminator and the efficiency of the road scraper is increased to a very marked degree.

20 The chatter eliminator may be mounted upon the scraper blade near the ends thereof, preferably one at each end, with a bracket which pivotally supports the brace of the chatter 25 eliminator which extends toward the ground and which is adjustable. A shoe which is adapted to ride upon the ground is carried by the end of the brace, or a suitable truck with wheels may be carried on the end of the brace so that the wheels will travel over the road. This structure forms a brace extending from the blade of the scraper down onto the ground and I have found that it accomplishes the very desirable 30 result of decreasing the repairs upon the patrol units, as well as permitting the scraper blade to spread the material under the same without creating a chatter. Further, with this chatter 35 eliminator attachment on the scraper blade, the patrol unit may be operated to cut the 40 ripple or washboard-like surface off of the road in a single operation.

Once a road becomes of a washboard-like 45 nature or irregular with little ruts in the same, it is difficult for the patrol scraper unit to again build the road into a smooth uniform surface for the reason that if the patrol unit passes over a washboard-like road the vibrations of the wheels dropping into the little recesses in 50 the road are magnified by the time they reach

the ends of the scraper blade, and the result is that the scraper blade just vibrates and chatters to dig the road up and make it even in a sense worse than before, because it helps to build up the irregular road surface. Heretofore it has been difficult for the blade of the scraper to be held steady enough and yet be adjustable so that it would not chatter in its operation. If the scraper blade of the patrol unit chatters in traveling over the road, the result is that the road will be uneven. With my chatter eliminators even though the patrol unit frame is of considerable size from end to end, the blade of the patrol unit can be carried steadily so as to pass evenly over the road to make in a faster and single operation a smoother surfaced road. Thus the wear and tear on the patrol unit and in fact on all of the road machinery becomes less and the maintenance of roads is decreased in cost by the use of my device which is of a simple and practical character for use with patrols and other scraper units in the maintenance of roads.

In the drawings:

Figure 1 illustrates a road patrol unit with my chatter eliminators in operative position.

Figure 2 illustrates a plan view of a road patrol unit.

Figure 3 illustrates an enlarged detail of one of my chatter eliminator units.

Figure 4 is a plan view of the chatter unit of Figure 3.

Figure 5 illustrates a roller bottom for the chatter unit, only the lower end of the unit being illustrated.

The patrol or scraper unit A is formed with an angle iron frame 10 which forms the bridge of the unit A and which usually extends from the front wheels 11 to the rear wheels 12. This bridge portion 10 is set up so as to permit the scraper blade B of the unit to be adjustably carried beneath the same.

The scraper blade unit B is mounted upon a frame 12' which is hung from the bridge 10 so that it can be raised and lowered either by the handle 13 or other suitable operating means which may extend to the tractor which pulls the patrol unit A. Neither the tractor nor the means for operating the same from the rear of the tractor are illustrated in the drawings. Usually the scraper blade unit B is operated by the control means so that either end of the blade unit B may be raised or lowered so as to adjust the scraping angle of the same.

The patrol unit A is also provided with means

so that the blade unit B may be set at an angle so as to carry the dirt from one side to the other of the road or in the opposite direction.

To overcome the chattering of the scraper 5 blade unit B I provide a chatter eliminator unit C which is formed with a bracket 14. This bracket 14 may be mounted directly on the back of the scraper blade unit B so as to be held rigidly secured thereto just above the reinforcing angle member 15 carried by the lower end of the unit B. Pivotaly connected by the king bolt 16 extending through the outer end of the bracket 14 I provide a brace which is formed with the attaching end portion 17 adapted to fit between the 10 ends 18 of the bracket 14 and through which the king pin 16 passes.

The brace includes a bottom link 19 which is pivotally connected at 20 to the lower end of the head member 17, while the other end of the link 20 19 is secured to an angularly-shaped end member 21 which pivotally supports at 22 the road shoe 23. The end member 21 is pivotally connected at 24 with an adjusting link rod 25 which extends to pivotally connect at 26 with the upper end 25 of the head portion 17. These parts form the brace of the chatter unit C. The adjustable link rod 25 may be lengthened or shortened by operation of the handle 27 carried by the upper end of the rod 25. This lengthens or shortens the connecting link rod 25 so as to raise or lower the shoe 23. The shoe 23 may be substituted by a truck D as illustrated in Figure 5 which may be provided with one or two supporting wheels 28. These wheels 28 take the place of the contacting portion of the shoe 23 of the chatter eliminator C.

The chatter eliminator C is adapted to be connected or secured to the ends of the blade unit B as illustrated, and by placing one of these units 40 at each end of the blade B I provide a bracket or brace road contacting member which extends from the blade B to the ground or road and holds the scraping edge 30 of the blade B steady as it passes over the road. With this chatter eliminating unit C it is virtually impossible for the cutting edge 30 of the scraper blade B to vibrate and chatter as heretofore as the patrol unit passes over the road. I have found that with these chatter eliminators the patrol unit A may be passed 50 comparatively fast over the road as compared to the operation heretofore so that a greater mileage may be covered by a single patrol unit and thus the cost of maintaining the road is materially reduced. The chatter eliminator C does not 55 only permit the blade B to operate more efficiently in smoothly grading the road surface but it will permit a patrol unit such as A to travel over the road surface and in a single operation provide a smooth level surface such as has been impossible 60 to accomplish in the same operation heretofore.

The link 19 may be replaced by means of an adjustable link 19' if desired as illustrated in Figure 5 of the drawings. Between the sides of the link 19', a slidale member 32 which is connected 65 pivotally at 20 to the lower end of the head member 17 is positioned. This member 32 is slidale with relation to the member 19' and is guided by means of a rod 33 secured to the member 32 which extends into an aperture 34 in the end member 70 21. A coil spring 35 is interposed between the member 32 and the end member 21 to provide spring tension between these parts. Thus, the truck D is held downwardly against the surface of the road by means of spring tension of the spring 75 35.

The shoe 23 in proper form is provided with side flanges 36 which prevent the spreading of the dirt forming the road from underneath the shoe. Accordingly, the shoe 23 is not allowed to push the dirt from beneath the same to either side of the shoe and the shoe 23 is prevented from digging a groove in the road.

The chatter eliminator C will follow along in back of the blade B in the operation of the patrol unit A and the brace may swing from side to side with the road contactor as illustrated in dotted outline in Figure 4. This permits the unit C to adjust itself automatically as the scraper blade B is adjusted so that no matter at which angle the blade B extends, the unit C will adjust itself accordingly to follow along in back of the blade B comparatively closely related to the cutting edge C, that is, the contact of the unit C with the road surface is closely positioned to the cutting edge 30 of the blade B. This overcomes chatter of the cutting edge 30 and permits the scraper blade unit B to evenly spread the road material over the surface of the road.

The upkeep on patrol units and road maintenance equipment is less by the use of my chatter 100 eliminator, because of the ease of operation of the same over the road. It will be noted that in the operation of a patrol unit such as A, if the rear wheels 12 drop into a recess in the road, a jar or vibration is directed to the bridge 10 which in turn 105 is carried on through to the cutting or scraping edge 30 of the blade B. By the time the vibration has reached the outer end of the blade B it has been magnified or increased to such an extent that it has been found that the scraper blade B 110 of the unit like A, instead of smoothing the road out, will help to chop it up into ruts like that which is termed a washboard road. Then, when the road is of a washboard-like nature the ordinary patrol unit over the same without my chatter 115 eliminator only helps to increase the detrimental formation of the road. I have thoroughly used this chatter eliminator in maintaining roads and have found it to accomplish very desirable results which I believe have been needed for some time. 120 The structure is simple, and with these units the patrol unit A may be operated very swiftly over the road.

In accordance with the patent statutes I have described the principles of operation of my chatter 125 eliminator and while I have endeavored to set forth the best embodiment thereof, the illustrations are only suggestive to those who are skilled in the art and the invention is defined within the scope of the following claims.

I claim:

1. In combination, a road scraper unit, a scraper blade mounted between the ends of said unit, a chatter eliminator secured to said blade including, a road contacting shoe, pivotal connecting means on said blade, a link pivotally connecting said shoe and said connecting means, and means for pivotally adjusting the link to pivot said shoe into contact with the surface of the road over which said scraper blade is adapted to travel.

2. A scraper blade chatter eliminator including, a road contacting element, pivotal connecting means on said scraper blade, a link pivotally connecting said pivotal connecting means and said road contacting element, and a link rod adjustable in length connecting the end of said link secured to said road contacting element and said pivotal connecting means to pivot said link.

3. A chatter eliminator for road scraper blades 150

- including, a bracket member adapted to be secured to the scraper blade, a king pin connecting link, adjustable linkage extending from said king pin link, a road shoe and a connector member pivotally secured to said shoe and adapted to connect said adjustable linkage to said shoe. 5
4. A road scraper blade chatter eliminator including, a bracket member secured to the scraper blade, a road contacting member, a connector pivotally secured to said road contactor, a king pin connector carried by said bracket member, and adjustable linkage connecting said king pin connector and said connector carried by said road contacting member, whereby said road contacting member may be adjustably positioned in relation to the cutting edge of the scraper blade to bear upon the ground adjacent the cutting edge of the scraper blade to provide an adjustable and self-aligning brace for the scraper blade to prevent chattering of the same. 15
5. A road scraper chatter eliminator including, a bracket member adapted to be supported on a scraper blade, a pivotal link secured thereto, a shoe carried by said link, and means for pivoting said link to force said shoe into engagement with the surface of the ground. 20
6. A road scraper blade chatter eliminator including, a bracket adapted to be supported by the scraper blade, a head portion pivotally secured to said bracket, a link pivotally secured to said head portion, a shoe secured to said link, and means for pivoting said link and shoe into engagement with the surface of the ground. 25
7. A chatter eliminator for road scrapers including, a bracket on the scraper blade, a road contacting shoe, a link pivotally connecting said shoe and said bracket, and an adjustable link rod between said bracket and said shoe to adjust the pivotal relation of said bracket and the link. 30
8. A chatter eliminator for road scrapers including, a bracket on the scraper blade, a road contacting shoe, a link pivotally connecting said shoe and said bracket, and means for holding said shoe and link in any adjusted position with relation to said bracket. 35
